UNITED STATES PATENT OFFICE.

WILLIAM L. CHURCH, OF NEWTON, MASSACHUSETTS, ASSIGNOR TO AMBURSEN COMPANY, OF BOSTON, MASSACHUSETTS, A CORPORATION OF NEW JERSEY.

PAVING FOR EARTH-FILL DAMS.

1,099,487.

Specification of Letters Patent.

Patented June 9, 1914.

Application filed August 27, 1913. Serial No. 786,825.

To all whom it may concern:

Be it known that I, WILLIAM L. CHURCH, citizen of the United States, and resident of Newton, in the county of Middlesex and 5 State of Massachusetts, have invented new and useful Improvements in Paving for Earth-Fill Dams, of which the following is a specification.

My invention relates to dams and more 10 especially to earth-fill dams.

Heretofore the up-stream or water-exposed face of earth-fill dams for reservoirs and the like has been provided with a paving consisting of hand-planed uncemented 15 stones; or blocks of concrete cast in place thereon and extending from crest to foot. It has been found, even in the case of reservoirs, that even a slight wave action on the joints between the sections of such paving 20 washes out the earth, thereby creating caverns in the face of the dam and greatly weakening the structure. Furthermore, because of the impracticability of erecting enclosing forms on the sloping up-stream face 25 of the dam, it is impossible to use concrete having sufficient fluidity to insure proper crystallization or setting, so that after such caverns have been created, subsequent wave action causes the rapid disintegration of the 30 paving.

It is therefore the object of my invention to provide an impermeable and substantially monolithic paving for the up-stream face of an earth-fill dam and the like, which shall 35 not be subject to the defects above set forth.

My invention involves the substitution for concrete paving, cast relatively dry on the face of the dam, of concrete blocks separately cast "slop-wet" on the river-bank, 40 or at some point convenient to the dam, and afterward placed in position on the dam face, together with means for protecting the joints between the blocks and binding the whole into a substantially monolithic mass, 45 and it involves also other features of novelty hereinafter more fully described and set forth in the appended claims.

One embodiment of my invention is illustrated in the drawings which accompany 50 and form a part of this specification; but it will be understood that the particular construction therein shown may be materially modified without departing from the principle of my invention.

In the drawings:—Figure 1 is a transverse

section of an earth-fill dam or reservoir; Fig. 2 is a longitudinal section taken on the line 2; Fig. 3 is a plan view of a concrete block employed in my improved paving; and Fig. 4 is a transverse section of the block 60 shown in Fig. 3.

In the particular drawings selected for more fully disclosing my invention, 1 represents a block of concrete or the like cast, preferably, "slop-wet", that is, the mixture 65 contains sufficient water to insure the thorough hydration of the cement and the proper setting of the concrete. The block may conveniently be three feet square and four inches thick, and preferably it is reinforced 70 with the wire mesh or other foraminous member 2. The outer face and upright sides of the block are indented as shown at 3, so that grooves will be formed in the outer face of the paving when the blocks are placed 75 side by side, and preferably the indentation of the outer face of the block is on an angle as shown, so that such grooves, so formed by abutting blocks, will be wider at the bottom than at the top, although this is not essential. 80

After the blocks have set, they are laid on the up-stream face of the dam 11 as shown in Fig. 1 and are provided with a coating of cement 10, such coating preferably being applied in the following manner: 85 Reinforcing rods 4 of any suitable construction are placed in the grooves between abutting blocks and suitably spaced from the bottoms thereof. Then wire mesh 6, or other suitable reticulated reinforcing material, is spread on the outer face of the blocks and slightly spaced therefrom by pieces of stone or other suitable means. The cement layer 10 is then applied, preferably by means of the cement gun which 90 forcibly projects cement against the blocks and fills the grooves and the space between the mesh 6 and the outer face of the blocks and also completely incloses the mesh, such cement layer, which may be about one inch 95 thick, uniting with the blocks and thereby binding the whole into one monolithic structure. 100

It is desirable to provide the paving with expansion joints at suitable intervals, say, 105 for example, every fifty feet. For this purpose the paving may be divided into sections, each containing a number of blocks, and the several sections separated by joints 9 produced in any convenient manner. For 110

example, a suitable upright form may be placed at the outer edge 5 of a section, and then, after the cement layer 10', which is laid up to the form, has set, a strip of paper 5 or the like is placed against said edge of the section and the cement layer 10 of the adjacent section is laid with its outer edge against said paper strip. When the cement layers 10, 10' harden, a suitable expansion 10 joint 9 will be left between the same, thereby permitting the free contraction of the cement layers in cold weather and their subsequent expansion in hot weather without producing cracks in the surface. In order 15 to protect the joints between two adjacent sections and prevent the washing out of the earth by the action of the waves, I prefer to place a strip 7 of flexible, yielding and water-resisting material, such as lead, rubberoid and the like, in the bottom of each 20 groove between adjacent sections and in such case I may employ two reinforcing rods 8, 8', slightly spaced above said strip, one such rod, as 8, being embedded in the 25 cement layer 10 and the other 8' in the layer 10'. It will be understood, of course, that two or more of these flexible strips, which may be about one-eighth of an inch thick, may be employed. Preferably the rods 8, 30 8' are slightly smaller in diameter than the rods 4.

Throughout the claims I employ the term "concrete" as covering cement and the like.

I claim:-

- 35 1. In an earth-fill dam having an inclined up-stream face, a paving for said face comprising cast concrete blocks and a coating of cement cast on the outer faces of said blocks and binding the whole into a substantially monolithic mass.
- 40 2. In an earth-fill dam having an inclined up-stream face, a paving for said face comprising cast concrete blocks arranged in sections, each section consisting of a plurality of said blocks and being separated from its contiguous sections by expansion joints.
- 45 3. In an earth-fill dam having an inclined up-stream face, a paving for said face comprising cast concrete blocks arranged in sections, each section consisting of a plurality of said blocks and being separated from its contiguous sections by expansion joints, and means for protecting said expansion joints from the action of the water.
- 50 4. In an earth-fill dam having an inclined up-stream face, a paving for said face comprising cast concrete blocks, each having its upper edges indented, and a coating of cement on the outer faces of said blocks, said coating of cement filling the grooves formed by the indentations between two abutting blocks.
- 55 5. In an earth-fill dam having an inclined up-stream face, a paving for said face comprising cast concrete blocks, each having its

upper edges indented to form one-half of a dove-tail groove, and a coating of cement on the outer faces of said blocks, said coating of cement filling the dovetail grooves formed between two abutting blocks.

6. In an earth-fill dam having an inclined up-stream face, a paving for said face comprising cast concrete blocks, each having its upper edges indented, a coating of cement on the outer faces of said blocks, said coating of cement filling the grooves formed by the indentations between two contiguous blocks, and a reinforcing rod in each of said grooves.

7. In an earth-fill dam having an inclined up-stream face, a paving for said face comprising cast concrete blocks, each having its upper edges indented, a coating of cement on the outer faces of said blocks, said coating of cement filling the grooves formed by the indentations between two abutting blocks, a layer of foraminous material embedded in said coating of cement, and a reinforcing rod in each of said grooves.

8. In an earth-fill dam having an inclined up-stream face, a paving for said face comprising cast concrete blocks, a coating of cement on the outer faces of said blocks, and a layer of foraminous material slightly raised from the outer faces of said blocks and embedded in said coating of cement.

9. In an earth-fill dam having an inclined up-stream face, a paving for said face comprising cast concrete blocks arranged in sections, each section containing a plurality of said blocks and being separated from its contiguous sections by expansion joints, the upper edges of each block being indented, and a layer of yielding, water-resisting material in the bottom of each groove formed by the indentations between the abutting blocks of adjacent sections.

10. In an earth-fill dam having an inclined up-stream face, a paving for said face comprising cast concrete blocks arranged in sections, each section containing a plurality of said blocks and being separated from its contiguous sections by expansion joints, the upper edges of each block being indented, a layer of yielding, water-resisting material in the bottom of each groove formed by the indentations between the abutting blocks of adjacent sections, and a layer of cement on the outer face of each section, each of said layers of cement filling a portion of one of said grooves.

11. In an earth-fill dam having an inclined up-stream face, a paving for said face comprising cast concrete blocks arranged in sections, each section containing a plurality of said blocks and being separated from its contiguous sections by expansion joints, the upper edges of each block being indented, a layer of yielding, water-resisting material in the bottom of each groove formed by the

indentations between the abutting blocks of adjacent sections, a layer of cement on the outer face of each section, each of said layers of cement filling a portion of one of said grooves, and a reinforcing rod embedded in the cement in each of said portions.

In testimony whereof, I have hereunto

subscribed my name this 26 day of Aug., 1913.

WILLIAM L. CHURCH.
